(57) **CLAIM**

The ornamental design for a lid for a container, as shown and described.

DESCRIPTION

FIG. 1 is a top, front, right side perspective view of a lid for a container of the new design.

FIG. 2 is a front elevation view thereof.

FIG. 3 is a rear elevation view thereof.

FIG. 4 is a left side elevation view thereof, the right side elevation view being a mirror image of the left side elevation view.

FIG. 5 is a top plan view thereof.

FIG. 6 is a bottom plan view thereof; and,

FIG. 7 is a cross-sectional view taken in the direction of line 7-7 shown in FIG. 2.

The broken lines are shown for the purpose of illustrating parts of the article that form no part of the claimed design.

1 Claim, 3 Drawing Sheets
